WELL TESTER

Reuben C. Baker, Coalinga, Calif., assignor to
Baker Oil Tools, Inc., Vernon, Calif., a corpora-
tion of California

Application December 9, 1947, Serial No. 790,519

17 Claims. (Cl. 166—12)

1

The present invention pertains to sub-surface well tools, and more particularly to testers for determining the sealing efficiency of cement or plastic materials, after they have set and hardened behind casing or liners, or for determining the productivity of oil or gas formations.

In well testers of certain types, such as those adapted to be set in well casings or liners, the tester is run in the well bore on the end of a tubular string, a valve mechanism preventing the well fluid from entering the tester and tubing string. The tester includes a packer designed to seal against the casing or liner wall and prevents the hydrostatic head of drilling mud or other casing fluid from being imposed upon the formation being tested.

Usually the tester is run in the well bore with the packer retracted and the valve closed. As indicated above, the tubing string is normally dry, although under some conditions it may be partially filled with a liquid. Upon reaching the point at which the testing operation is to occur, the packer is expanded against the casing and the tester valve is then opened, to allow the formation fluid, if any, to flow through the tester into the tubing string to which it is connected. After the valve has remained open for a predetermined time, any fluid that may have passed through the tester is entrapped therein and in the tubing string. This fluid sample is then withdrawn with the tester to the top of the well bore.

It is an object of the present invention to generally improve well testers of the character indicated.

Another object of the invention is to provide an improved valve mechanism for controlling passage of fluid into or through the tester.

A further object of the invention is to provide an improved valve mechanism, which can be repeatedly opened and closed, if desired, to determine fluid flow into and through the tester.

Still another object of the invention is to provide an improved tester valve mechanism, which can be opened at will to various extents while the tester is set in the well bore.

A further object of the invention is to provide a well packer having an improved valve device for controlling the by-passing of fluid around the packing element of the packer, which effects a seal with the wall of a casing or liner in which it is positioned.

The invention has other objects which will become apparent from a consideration of the embodiments shown in the drawings accompanying and constituting part of the present specifici-

5 cation. These forms will now be described in detail to illustrate the general principles of the invention; but it is to be understood that such detailed description is not to be taken in a limited sense, since the scope of the invention is best defined by the appended claims.

Referring to the drawings:

Figures 1a and 1b together comprise an elevation of a well tester in a casing string, with the parts in the position they occupy while the tool is being moved through the casing. Figure 1b actually forming a lower continuance of Figure 1a;

Figures 2a, 2b and 2c together constitute an enlarged longitudinal section through the tester, 15 with the parts occupying the same relative position as in Figures 1a and 1b;

Figures 3a, 3b and 3c are views similar to Figures 2a, 2b and 2c, illustrating the well tester with its parts in another operative position.

Figure 4 is a cross-section taken generally along the line 4—4 on Figs. 1a and 2a;

Figure 5 is a cross-section taken generally along the line 5—5 on Figs. 1a and 2a;

Figure 6 is a cross-section taken generally along the line 6—6 on Fig. 2a;

Figure 7 is an exploded, elevational and sectional view of the cam mechanism for controlling the main valve of the tester.

Fig. 8 is a partial longitudinal section through a modified form of tester valve mechanism; and

Fig. 9 is a view similar to Fig. 8, with the parts in another operative position.

As disclosed in the drawings, the formation tester A is movable longitudinally through a well casing B on the lower end of a tubular string C, such as drill pipe or tubing. The formation tester A includes a lower valve mechanism D, an intermediate packer E, and an upper control mechanism F for the valve and for setting and releasing the packer.

The valve mechanism D is adapted to admit fluid, or prevent fluid from passing, into the tester A and tubing string C, and is capable of preventing such fluid from flowing out of the tubing string and tester. This valve mechanism includes a lower perforated or slotted nipple 10 of any desired length, having its bottom end closed by a cap 11, and its upper end threaded into a sub 12 threaded into a valve housing 13. The upper end of the sub 12 is provided with a valve seat 14 adapted to be engaged by a valve element or ball 15 upon downward movement of the latter, to prevent downward flow of fluid from the tester. This ball and seat 15, 14 actually constitute a check valve, with the ball movable

upwardly from the seat to permit passage of fluid into the tester. Its extent of upward movement is limited by a stop in the form of a pin 16 secured to and extending across the valve housing 13 above the ball 15.

Threaded or otherwise secured to the valve housing is a valve body 17, having its upper end threadedly attached to the lower end of the tubular mandrel 18 of the well packer E. Leakage between the body 17 and housing 13 may be prevented by a side seal 19, the latter engaging the inner wall of the body 17.

The valve housing 13 contains a valve head 20 adapted for upward movement into engagement with a valve seat 21 formed in the housing. A valve stem 22 is attached to and projects upwardly from the head, passing from the housing into the lower end of the valve body 17. Threaded on the upper end of the stem 22 is a spring retainer 23 secured in place by a suitable lock nut 24. The valve head 20 is urged upwardly into engagement with its seat 21 by a helical compression spring 25 surrounding the valve stem 22, and confined between the retainer 23 and a central boss 26 integral with and projecting upwardly from the main portion of the valve housing 13. This boss has a plurality of generally radial ports 27 extending through its side wall, in order to establish communication between a central chamber 28 in the valve housing 13, surrounding the valve stem 22, and the interior of the valve body 17.

It is apparent that the compressed spring normally tends to maintain the valve head 20 in an upward position in engagement with its seat 21, to prevent fluid from passing through the perforated nipple 18 and around the lower valve ball 15 into the valve body 17, from which it would otherwise continue travelling upwardly through the remainder of the tester and into the tubing string C. This valve may be opened at the will of the operator, located at the top of the well bore, upon downward movement of a valve rod 29 extending through the tubular packer mandrel 18. This valve rod is normally maintained and is urged in an upward direction by a relatively strong compression spring 30, whose upper end is disposed within and engages a spring retainer 31 secured to the lower end of the valve rod 29, and whose lower end bears against the valve housing 13. The rod must be moved downwardly against the resisting force of the heavy return spring 30, in order to move the main tester valve 20 downwardly against the force of its closing spring 25, thus opening the tester and permitting fluids to pass therewith.

As described above, the operating rod 29 extends through the packer mandrel 18, there being substantial clearance between these elements to provide an annular passage 32 through which fluids can flow. This rod also extends through a sub or packer valve member 33 threaded on the upper end of the mandrel 18, and also through another sub 34 screwed into the upper end of the previously mentioned sub. For the purpose of guiding the rod, which may have a square cross-section, in its longitudinal movement within the mandrel 18 and subs 33, 34, a suitable ring or sleeve 35 may be secured within the upper sub 34, as by the use of welding material 36, this ring slideably engaging the rod 29 and also having a hole therethrough of square cross-section. In order to permit the fluid to flow upwardly around the rod, the guide ring or sleeve 35 has

a plurality of circularly spaced holes 37 therethrough.

The valve rod 29 is moved downwardly to open the main tester valve by a cam device forming part of the valve operating mechanism F. This device includes a lower driven face or axial cam 38 disposed over the rod and having a shoulder 39 resting upon a companion shoulder at the upper end of the valve rod. The square cross-sectional bore through the cam 38 below its shoulder ensures its coupling to the rod 29. A complementary driving face or axial cam element 40 is rotatable upon a cylindrical upper rod extension 29a, its lower cam surface 41 being engageable with the upper cam surface 42 of the other element. One form of cam configuration is disclosed most clearly in Fig. 7, although other specific forms could be used.

The driving cam element 40 is welded, or otherwise suitably secured, to an inner tubular member 43 rotatable within an outer barrel 44 threaded on the upper sub 34. The inner member 43 is prevented from moving longitudinally upward within the barrel 44 through engagement of a lower head 45 on the inner member with an intervening thrust washer 46, which, in turn, engages an inner shoulder 47 on the barrel. Downward movement is prevented by a suitable thrust bearing 48 disposed between the lower end of the inner member 43 and the upper end of the upper sub 34. As illustrated in the drawings, this thrust bearing may include upper and lower races 49, 50 and intermediate tapered roller elements 51 in contact therewith.

It is apparent that the inner member 43 and the upper cam element 40 secured thereto are rotatable with respect to the barrel 44, upper sub 34, lower cam element 38 and rod 29. Since the upper cam element 40 cannot move axially, its rotation produces downward axial movement of the other element 38 and valve rod 29, to effect opening of the main tester valve 20.

The inner member 43 of the valve operating mechanism F is attached to the lower end of the tubing string C through the agency of a collar 52. This inner member 43 is also adapted to impart rotation, under some circumstances, to the outer barrel 44, upper and lower subs 34, 33 and packer mandrel 18 through a slipping clutch. The latter includes a plurality of segments 53 having cylindrical inner faces frictionally engaging the exterior of the inner member 43, and downwardly and inwardly tapered external surfaces 54 engaging a companion tapered surface 55 at the upper end of the barrel 44. The segments 53 are preferably prevented from rotating relative to the barrel by one or more pins 56 secured to the barrel 44 and extending inwardly between a pair of adjacent segments.

The frictional coupling force between the segments 53 and inner member 43 is provided by a helical compression spring 57 disposed around the inner member, with its lower end bearing against the segments 53, to press them downwardly into the tapered portion 55 of the barrel and radially inward against the inner mandrel 43. The upper end of the spring 57 bears against an adjustment nut 58 threaded on the inner member and rotatable thereon to determine the degree of spring compression. This nut is held in adjusted position by a suitable lock nut 59.

The well packer E, which forms the intermediate part of the testing tool, includes the tubular mandrel 18 connected to the valve mechanism D and also to the valve control mechanism F,

through the agency of the subs 33, 34. A tubular body 60 surrounds the mandrel in spaced relation to form an annular passage 61 through which fluid may flow in by-passing a packing element 62, of rubber or similar material, surrounding the body and bearing at its upper end against a retainer and valve head 63 threaded on the body, and at its lower end against a ring 64 threaded on a tapered slip expander 65. The body 60 is movable downwardly with respect to the ring 64 and expander 65 for the purpose of compressing the packing sleeve 62 and forcing it outwardly into leakproof engagement with the casing wall. Upward movement of the body relative to the ring and expander is limited by engagement of a body shoulder 66 with a corresponding shoulder 67 on the ring 64. The expander 65, and mandrel are non-rotatably splined to each other by keys 99 secured to the mandrel slideable in keyways 100 in the expander.

For the purpose of anchoring the tester at any desired location in the well casing, a plurality of slips 68 is mounted upon the tapered expander 65. These slips have inner faces 69 inclined in downward and inward direction, and slideable along companion tapered faces or surfaces 70 on the expander element 65. It is apparent that downward movement of the expander within the slips 68 shifts the latter radially outward and forces their external wickers 71 into the wall of the well casing B.

In order to ensure conjoint movement of the slips 68, they are each pin connected to the upper end of a link 72, the lower end of which is pivotally mounted within a ring 73 loosely mounted upon the mandrel 18. This ring 73 is connected to the upper collar 74 of a drag and lock device 75 by means of a swivel connection 76, to permit rotation of the slip ring without rotating the drag device. As disclosed in the drawings, this swivel connection may be constituted by a sectional tie ring 77 secured to the upper collar 74 of the drag device by screws 78 or the like. The tie ring including upper and lower inwardly directed flanges 79 disposed within companion external grooves in the slip ring 73 and collar 74, thereby providing the desired swivel connection permitting relative rotation between the slip ring and drag device, while ensuring their joint longitudinal movement.

The drag and lock device 75 includes a lock pin 80 secured to the mandrel 18 and movable within a J or L slot, comprising a longitudinal portion 81 terminating in an upper horizontal locking portion 82. The drag device further includes a plurality of circularly spaced, outwardly bowed springs 83 frictionally engaging the casing wall, and having their upper ends secured to the collar 74, as by means of an encompassing ring 84 and set screws 85. Their lower ends are similarly secured to a lower collar 86 slideable upon the mandrel 18.

The annular passage 61 through the body 60 and around the packing element 62 may be closed by a valve device mounted upon the lower sub 33. This valve device has a cylindrical valve head 87 adapted to fit snugly within a corresponding cylindrical valve seat 88 formed within the upper packing retainer 63 threaded on the body 60. The valve head 87 is inserted into the seat 88 to the extent determined by engagement of the lower end of the head with a shoulder 89 integral with the retainer 63.

Leakage between the cylindrical head 87 and seat 88 is prevented by one or more seal rings 90.

such as round rubber seals, carried within one or more ring grooves 91 in the head 87 and adapted to engage the cylindrical seat 88.

In order to protect the round seals 90 of rubber or similar material while the head 87 is disposed out of the seat 88, or in open position, a protecting sleeve cover 92 is normally maintained over the seal or seals by a spring 93 surrounding the lower sub 33, with its lower end engaging the upper end of the sleeve cover 92, and its upper end engaging a shoulder 94 on the sub. The extent of downward movement of the cover along the sub under the action of the spring 93 is limited by engagement of a pin 95 secured to the sub 33 with the upper end of a longitudinal slot 96 in the sleeve 92.

Downward movement of the head 87 within the retainer 63 to close the by-pass passage 61 not only moves the head within the valve seat 88, but also causes the lower end 92a of the cover 92 to engage the upper end of the retainer 63 and move it relatively upwardly along the sub against the action of the spring 93, until it has been removed fully from engagement with the round rubber seal or seals 90, allowing them to engage the cylindrical seat 88 and perform their sealing function. Upon elevation of the valve head 87 from its seat 88, to again expose the seals 90, the spring 93 shifts the cover 92 back over the seals 90 to protect them from damage.

The formation tester is made up at the top of the well bore with the slips 68 and packing 62 in retracted positions, as determined by location of the mandrel lock pin 80 within the horizontal locking portion 82 of the J or L slot. With the pin in this position, the slips and packing element are not only held in retracted positions, but the valve head 87 is maintained in elevated position above the mandrel seat 88, to hold the annular by-pass passage 61 open. The cam elements 38, 40 have also been so disposed as to cause their longitudinal faces 97, 98 to co-engage, which ensures disposition of the valve operating rod 29 in its uppermost position, in which the spring retainer 31 on the lower end of the rod is disengaged from the valve stem 22, in order to allow the valve spring 25 to close the valve head 20.

The tool is mounted on the lower end of the tubular string C and is run in the well casing B with the parts relatively related as just described and as illustrated in Figures 1 and 2. Ordinarily, the tubing string C and interior of the tester A above the main valve D are dry, containing nothing more than air at atmospheric pressure. Occasionally, as is known in the art, some fluid may be placed in the tubing string after the tester has been run through the drilling mud or other casing fluid to a certain depth. When the point in the well casing B is reached at which the tester is to be set, the tubing string C is turned slightly, as to the right, the rotational force being transmitted from the tubing string to the tubular inner member 43, and, by virtue of the frictional engagement of the latter with the segments 53, to the upper barrel 44, which, in turn, transmits the rotation through the upper and lower subs 34, 33 to the packer mandrel 18. Rotation of this mandrel moves its lock pin 80 out of the horizontal lock slot portion 82 and into the longitudinal slot portion 81.

The tubing string C may now be lowered, causing the mandrel 18 to be lowered, its lock pin 80 moving downwardly within the longitudinal slot 81. The upper lock collar 74 containing the slot will not move downwardly, since such motion is

resisted by the frictional engagement of the drag springs 83 with the casing B. During lowering movement of the mandrel 18 and the sub 33 connected thereto, the valve head 87 is moved into the cylindrical valve seat 88, to close the bypass passage 61, until the end of the head 87 engages the retainer shoulder 89. Continued downward movement of the mandrel and sub connected to it then moves the retainer 63, tubular body 60, packing element 62 and tapered expander 65 downwardly, shifting the last-mentioned part within the slips 68, which are prevented from downward movement by the drag device 75. As a result, the slips 68 are forced outward into anchoring engagement with the well casing B, in view of the wedging action of the expander 65, preventing further downward movement of the latter.

Additional downward movement of the tubing string C will now move the retainer and abutment member 63 and packer body 60 downwardly relative to the expander 65, compressing the packing sleeve 62 in the longitudinal direction and expanding it radially outward into firm sealing engagement with the casing B, to close the annulus between the well packer E and casing.

Packing off of the annulus around the well packer and testing tool thus relieves the formation to be tested of the hydrostatic head of fluid in the well casing above the tester and ensures the passage of fluid into the tester when its main valve D is opened, in the event the formation pressure is greater than the atmospheric pressure in the tubing string.

Following the anchoring of the well tester in packed-off condition within the well casing B, the main tester valve D can be opened through rotation of the tubing string C, as to the right. Such rotation is transmitted through the inner tubular member 43 to the upper cam 40, which cannot move longitudinally, and which, therefore, moves the lower cam 38 and valve rod 29 longitudinally against the force of the spring 30, to cause engagement of the retainer 31 with the valve stem 22 and shifting of the valve head 20 down against the force of its closing spring 25. The tester is now open and any fluid in the formation can flow into it through the perforated nipple 10, to unseat the lower valve ball 15 and pass around the open valve head 20 into the central valve chamber 28, from which it can flow through the ports 27 upwardly around the spring retainer 31 and through the annulus 32 around the valve rod 29. In flowing upwardly around the valve rod, the formation fluid passes through the holes 37 in the guide ring 35, around the cam elements 38, 40, and through the holes 40a in the upper element into the inner tubular member 43, from where it will pass into the tubing string C.

The tubing string is rotated less than a complete revolution, in the particular design illustrated in the drawings, to effect full opening of the main valve D. When it is desired to close the main valve to prevent further flow of formation fluid into the tester, rotation of the tubing string C is continued in the same direction until the opposed faces 41, 42 of the cams ride off one another, as when the longitudinal faces 97, 98 are in substantial alignment with one another. The high point 42a on the lower cam is then 70 opposite the low point 41a of the upper cam, which allows the return spring 30 to shift the rod 29 upwardly to its initial position, and permits the valve spring 25 to re-engage the main valve head 20 with its seat 21. As assurance

5 that the main valve will be closed, the tubing string C may be rotated slightly to the left, after having partaken of a complete revolution, to positively re-engage the longitudinal cam faces 97, 98 with one another.

10 The tester may now be released and withdrawn from the well casing. All that need be done is to elevate the tubing string C, which will move the valve head 87 out of the cylindrical seat 88, opening the bypass passage 16 and equalizing the hydrostatic pressure on both sides of the packing element 62. Continued upward movement of the tubing string moves the upper retainer 63 away from the lower expander 65 and allows the packing element to retract to its initial position free from contact with the casing wall. Further upward movement of the tubing string causes the keys 99 secured to the mandrel 18, to engage the upper expander ring 64 and pull the expander 65 upwardly with respect to the slips 68, since the latter are restrained from similar movement by engagement of the drag springs 83 with the casing B. This action retracts the slips from the casing in view of their dovetailed connection 25 with the expander.

20 The elements of the tool are now in condition for withdrawal of the tester to the top of the well casing. Any fluid that may have entered the tester and tubing string are prevented from flowing out of the tester by downward closing of the valve ball 15 against its seat 14. If desired, the tubing string C may be rotated slightly to the left to reposition the lock pin 80 in the horizontal slot portion 82, to hold the parts locked in their retracted positions during elevation of the tool within the well casing.

25 Because of the configuration of the coengaging cam elements 38, 40, the operating rod 29 and the main valve head 20 may be moved downwardly to various extents, when the tester is anchored in pack-off condition within the casing B, depending upon the extent of rotation of the driving cam 40 with respect to the driven cam 38. It is apparent from an inspection of the figures, and particularly Fig. 7, that a slight angular movement of the driving cam 40 will effect movement of the valve rod and valve head to a comparatively slight extent, to correspondingly open the main valve head 20 slightly.

30 As the angular movement of the driving cam 40 increases, the extent of valve head opening also increases, until a maximum is reached, wherein the high points 41a, 42a of the two cams are on the verge of riding off one another, which will occur after substantially a complete revolution of the driving cam 40. A slight turning of the latter beyond one full revolution will cause the high points to ride off one another, and will allow the heavy spring 30 to shift the rod 29 back to its initial position, and allow the valve spring 25 to re-engage the valve head 20 with its seat 21, thereby closing the main valve D.

35 After the main valve has been closed, it can be re-opened by merely continuing rotation of the tubing string C and the driving cam 40 in the proper direction, as to the right. For that matter, the tubing string and driving cam connected to it may be rotated as often as desired, to effect alternate opening and closing of the main valve D. Thus, the main valve may be opened repeatedly, if desired, through a simple manipulation of the tubular string, and the extent of opening can be regulated in dependence upon the degree of angular movement of the tubing string C and the driving cam 40 from the initial position of

the latter, with its longitudinal face 97 in full bearing contact with the corresponding longitudinal face 98 of the driven cam 38.

Following anchoring of the well packer E in pack-off condition within the well casing B, it is evident that the packer mandrel 18 is prevented from rotating since the slips 68 are embedded in the casing wall, and in view of their dovetailed connection with the expander 65, prevent its downward movement and rotation in either direction. The slideable splined connection between the mandrel 18 and the tapered expander 65 in the form of the keys 99 and slots 100 prevents the mandrel 18 from rotating. As a result of preventing the mandrel from rotation upon anchoring of the slips 65 in the casing B, the upper and lower subs 34, 33 are also prevented from rotation, which precludes rotation of the valve rod 29, in view of its square or rectangular cross-section and its slideable fit in the guide 35 welded to the upper sub 34.

Accordingly, after the well packer E has been anchored to the casing B, the outer barrel 44 connected to the sub 34 and the driven cam 38 are prevented from rotating. Rotary movement of the inner tubular member 43 is still capable of occurring to rotate the driving cam 40 without rotating the barrel, because of the ability of the inner tubular member 43 to slip within the friction clutch segments 53.

Before anchoring of the well packer E to the casing B, however, all parts, with the exception of the drag device 75, are free from engagement with the casing. The segments 53 of the clutch exert sufficient frictional force against the inner tubular member 43 to cause its rotary movement to be imparted, without slippage, to the barrel 44, and from the latter member, through the subs 34, 33 to the mandrel 18, enabling the lock pin 80 to be moved from the horizontal lock portion 82 of the collar 14, whereupon the tubing string C may be lowered to cause the by-pass valve 81, 88 to be closed, the slips 65 to be anchored in the casing, and the packing element 62 to be fore-shortened and expanded against the casing wall. Thereafter, as above indicated, the inner tubular member 43 slips within the clutch segments 53, for the purpose of rotating the driving cam 40 with respect to the driven cam 38 and determine the opening and closing of the main tester valve D.

The efficiency of the valve device for controlling the by-pass passage 61 around the packing element 62, and its long life before replacement is necessitated, is indicated by the fact that the elastic seal ring 90 is not subject to compression due to the down weight imposed upon the tubing string C in setting the well packer in the casing. The only load impressed upon the seal ring is that of the hydrostatic head of fluid in the annulus above the packing element 62, and the formation pressure acting in an upward direction. In addition, the sealing element 90 is not exposed when the valve is in open position in view of the protection afforded by the retractable sleeve cover 92. Assurance is therefore had that the seal ring 90 will be in proper condition for entry into and sealing against the cylindrical seat 88 when the by-pass valve is to be closed.

Under some conditions encountered in the well bore, it is desired to pump fluid through the tester and into the formation. As an example, during the testing operation, the well may begin flowing under high pressure, and it may become

necessary to "kill" the well by pumping a fluent substance down the tubing string C.

The valve mechanism disclosed in Figs. 1 to 7, inclusive, does not permit downward pumping of fluid through the tubing string, since the ball valve 15 moves downwardly into sealing engagement with its seat 14. The valve mechanism illustrated in Figs. 8 and 9 permits downward pumping of fluids, while allowing the formation tester to function in its normal manner, as described in connection with the other embodiment of the invention.

As shown in Figs. 8 and 9, the valve housing 13a is threaded into the valve body 17. The perforated nipple 10a may be threaded into the lower end of the housing. In order to prevent downward flow of fluids, under normal operation of the formation tester, the ball valve 15 moves downwardly into engagement with a companion seat 14a formed in a sleeve valve 110 slideably mounted in the valve housing 13a. This sleeve valve is normally disposed over side ports 111 in the valve housing by one or more shear screws 112, there being a suitable side seal 113 mounted on the sleeve valve 110 for engagement with the valve housing above the ports 111 (see Fig. 8).

The valve mechanism operates in the same manner as the valve mechanism disclosed in the other embodiment of the invention. However, should it be necessary to pump fluids downwardly through the tubing string for outward passage from the formation tester below its packer E, the tubing string is filled with fluid. Sufficient pressure is imposed on this fluid to shear the screws 112 and shift the sleeve valve 110 downwardly to a position limited by its engagement with the upper end of the perforated nipple (Fig. 9). In this position, the ports 111 are open and the fluids can be pumped outwardly from the valve mechanism through them.

The shear screws 112 have sufficient strength to withstand a high hydrostatic head of fluid in the tubing string, in order to insure retention of the formation sample therein under normal use of the tester. The application of additional pressure to the fluid in the tubing string effects a shearing of the screws 112 and opening of the side ports 111.

50 The inventor claims:

1. A well tester: including imperforate tubular means on a tubular string and adapted to conduct fluid to said tubular string; valve means in said tubular means for controlling fluid flow into said tubular means; means for opening and closing said valve means, comprising a driven axial cam operatively connected to said valve means, a driving axial cam engageable with said driven axial cam, means for connecting said driving axial cam to said tubular string for manipulation thereby, and spring means engaging one of said cams to maintain said cams in engagement with each other when said valve means is closed.

65 2. A well tester: including imperforate tubular means on a tubular string and adapted to conduct fluid to said tubular string; valve means in said tubular means for controlling fluid flow into said tubular means; means for opening and closing said valve means, comprising an axial cam member and a follower member engageable therewith, one of said members being operatively connected to said valve means, means for connecting the other of said members to said tubular string for manipulation by said tubular

string, and spring means engaging said one of said members to maintain said members in engagement with each other when said valve means is closed.

3. A well tester; including tubular means on a tubular string and adapted to conduct fluid to said tubular string; valve means in said tubular means for controlling fluid flow into said tubular means; means for opening and closing said valve means, comprising a driven axial cam operatively connected to said valve means, a driving axial cam engageable with said driven axial cam, means for connecting said driving axial cam to said tubular string for rotation thereby in one direction to move said driven cam longitudinally in one direction to shift said valve means, said cams having coengaging tapered surfaces to effect alternate opening and closing of said valve means upon continuation in the rotation of said driving cam in the same direction through more than one revolution, and coengaging stop means on said cams to prevent longitudinal movement of said driven cam when said driving cam is rotated in the opposite direction.

4. A well tester; including tubular means on a tubular string and communicable with said tubular string to conduct fluid thereinto; valve means in said tubular means for controlling fluid flow into said tubular means; means for opening and closing said valve means, comprising a spring for urging said valve means to closed position, a driven axial cam, means connecting said cam to said valve means, a driving axial cam engageable with said driven axial cam, means for attaching said driving axial cam to said tubular string for rotation thereby to move said driven cam longitudinally and open said valve means, and spring means engaging said connecting means to maintain said cams in engagement with each other when said valve means is closed.

5. A well tester; including tubular means on a tubular string and communicable with said tubular string to conduct fluid thereinto; valve means in said tubular means for controlling fluid flow into said tubular means; and means for opening and closing said valve means, comprising a driven axial cam operatively connected to said valve means, and a driving axial cam engageable with said driven axial cam, means for connecting said driving axial cam to said tubular string for manipulation thereby; and co-engaging stop means on said cams for limiting their relative rotation.

6. A well tester; including tubular means adapted to be lowered in a well bore; normally retracted means disposed around said tubular means and adapted for expansion into engagement with the wall of said well bore; lock means on said tubular means for holding said normally retracted means in retracted position, said lock means being releasable by manipulation of said tubular means; a tubular member adapted for connection to a tubular string; releasable clutch means connecting said tubular member to said tubular means; valve means in said tubular means for controlling fluid flow into said tubular means; and means for opening and closing said valve means, comprising a driven axial cam connected to said valve means, and a driving axial cam engageable with said driven axial cam and connected to said tubular member.

7. A well tester; including tubular means adapted to be lowered in a well bore; normally retracted means disposed around said tubular means and adapted for expansion into engage-

ment with the wall of said well bore; lock means on said tubular means for holding said normally retracted means in retracted position, said lock means being releasable by manipulation of said tubular means; a tubular member adapted for connection to a tubular string; releasable clutch means connecting said tubular member to said tubular means; valve means in said tubular means for controlling fluid flow into said tubular means; and means for opening and closing said valve means, comprising an axial cam member and a follower member engageable therewith, means connecting one of said members to said valve means and means connecting the other of said members to said tubular member.

8. A well tester; including tubular means adapted to be lowered in a well bore; normally retracted means disposed around said tubular means and adapted for expansion into engagement with the wall of said well bore; lock means on said tubular means for holding said normally retracted means in retracted position, said lock means being releasable by manipulation of said tubular means; a tubular member adapted for connection to a tubular string; releasable clutch means connecting said tubular member to said tubular means; valve means in said tubular means for controlling fluid flow into said tubular means; and means for opening and closing said valve means, comprising a spring for closing said valve means, a cam member and a follower member engageable therewith, means connecting one of said members to said valve means, and means connecting the other of said members to said tubular member.

9. A well tester; including tubular means adapted to be lowered in a well bore; normally retracted means disposed around said tubular means and adapted for expansion into engagement with the wall of said well bore; lock means on said tubular means for holding said normally retracted means in retracted position, said lock means being releasable by manipulation of said tubular means; a tubular member adapted for connection to a tubular string; releasable clutch means connecting said tubular member to said tubular means; valve means in said tubular means for controlling fluid flow into said tubular means; and means for opening and closing said valve means, comprising a spring for closing said valve means, an axial cam member and a follower cam member engageable therewith, a rod extending through said tubular means and connecting one of said members with said valve means, and means connecting the other of said members to said tubular member for rotation therewith.

10. A well tester; including tubular means having a valve seat and adapted to be lowered in a well bore on a tubular string; valve means in said tubular means for controlling fluid flow between the interior and exterior of said tubular means, comprising a housing having a port therein, a sleeve valve adapted to be disposed over said port to close the same, means engageable with said sleeve valve to shift said sleeve valve to a position opening said port, a valve element movable upwardly into engagement with said valve seat to prevent upward flow of fluid into said tubular means, a downwardly closing valve device in said tubular means to prevent downward flow of fluid from said tubular means, means for shifting said valve element between open and closed positions, comprising an axial cam member and a follower member engageable therewith, means connecting one of said mem-

bers to said valve element, and means connecting the other of said members to said tubular means.

11. A well tester; including tubular means having a valve seat and adapted to be lowered in a well bore on a tubular string; valve means in said tubular means for controlling fluid flow between the interior and exterior of said tubular means, comprising a housing having a side port therein, a sleeve valve having a seat, means releasably securing said sleeve valve to said housing and over said port, a first valve element above said sleeve valve and movable upwardly into engagement with said valve seat of said tubular means to prevent upward flow of fluid into said tubular means, a second valve element movable downwardly into engagement with said sleeve valve seat to prevent downward flow of fluid from said tubular means through said sleeve valve, and means for shifting said first valve element between open and closed positions, comprising an axial cam member and a follower member engageable therewith, means connecting one of said members to said first valve element, and means connecting the other of said members to said tubular means.

12. A well tester; including elongate tubular means on a tubular string and adapted to conduct fluid to said tubular string; valve means in said tubular means; a rod device within said tubular means engageable with said valve means to operate said valve means; a driven axial cam non-rotatably secured to said rod device; means for preventing substantial rotation of said rod device relative to said tubular means; a driving axial cam rotatable relative to said rod device and having a cam face engaging a companion cam face on said driven axial cam to reciprocate the driven axial cam; means for preventing substantial movement in both longitudinal directions between said driving cam and tubular means; and means providing a connection for attaching said driving cam to said tubular string.

13. A well tester; including elongate tubular means on a tubular string and adapted to conduct fluid to said tubular string; a valve seat in said tubular means; a valve member engageable with said seat to prevent upward flow of fluid into said tubular means above said seat; spring means within said tubular means urging said valve member upwardly; a rod device reciprocable within said tubular means and engageable with said valve member to shift said valve member downwardly from its seat; spring means engaging said rod device to elevate it from said valve member; a driven axial cam non-rotatably secured to said rod device; means for preventing substantial rotation of said rod device relative to said tubular means; a driving axial cam rotatable relative to said rod device and having a cam face engaging a companion cam face on said driven axial cam; means for preventing substantial longitudinal movement between said driving cam and tubular means; and means providing a connection for securing said driving cam to said tubular string.

14. A well tester; including tubular means adapted to be lowered in a well bore; normally retracted means disposed around said tubular means and adapted for expansion into engagement with the wall of said well bore; lock means on said tubular means for holding said normally retracted means in retracted position, said lock means being releasable by manipulation of said tubular means; a tubular member adapted for

connection to a tubular string; clutch means connecting said tubular member to said tubular means and adapted to slip when a predetermined torque is imposed thereon by said tubular member; valve means in said tubular means for controlling fluid flow into said tubular means; and means for opening and closing said valve means, comprising an axial cam member and a follower cam member engageable therewith, means connecting one of said cam members to said valve means, and means connecting the other of said cam members to said tubular means.

15. A well tester; including tubular means having a seat and adapted to be lowered in a well bore on a tubular string; valve means in said tubular means for controlling fluid flow between the interior and exterior of said tubular means, comprising a housing having a side port therein, a sleeve valve adapted to be disposed over said port, means engageable with said sleeve valve to shift said sleeve valve to a position opening said port, a valve element movable upwardly into engagement with said valve seat to prevent upward flow of fluid into said tubular means, a downwardly closing valve device in said tubular means below said valve element to prevent downward flow of fluid from said tubular means, and means for shifting said valve element between open and closed positions, comprising an axial cam member and a follower member engageable therewith, means connecting one of said members to said valve element, and means connecting the other of said members to said tubular means.

16. A well tester; including tubular means having a valve seat and adapted to be lowered in a well bore on a tubular string; valve means in said tubular means for controlling fluid flow between the interior and exterior of said tubular means, comprising a housing having a side port therein, a sleeve valve in said housing and having a seat, means releasably securing said sleeve valve to said housing and over said port, a first valve element above said sleeve valve and movable upwardly into engagement with said seat of said tubular means to prevent upward flow of fluid into said tubular means, a second valve element movable downwardly into engagement with said sleeve valve seat to prevent downward flow of fluid from said tubular means through said sleeve valve, and means for shifting said first valve element between open and closed positions, comprising an axial cam member and a follower member engageable therewith, means connecting one of said members to said first valve element, and means connecting the other of said members to said tubular means.

17. A well tester; including tubular means having a valve seat and adapted to be lowered in a well bore on a tubular string; valve means in said tubular means for controlling fluid flow between the interior and exterior of said tubular means, comprising a housing having a side port therein, a sleeve valve having a seat, means releasably securing said sleeve valve to said housing and over said port, a first valve member movable upwardly into engagement with said valve seat of said tubular means to prevent upward flow of fluid into said tubular means, a second valve element movable downwardly into engagement with said sleeve valve seat to prevent downward flow of fluid from said tubular means through said sleeve valve, and means for shifting said first valve element between open and closed position,

15

comprising an axial cam member and a follower member engageable therewith, means connecting one of said members to said first valve element, and means connecting the other of said members to said tubular means.

REUBEN C. BAKER.
